(57) **CLAIM**

We claim the ornamental design for a battery-powered vacuum pump with filter for suctioning mucus from infant nasal passages, as shown and described.

DESCRIPTION

FIG. 1 is a perspective view of a battery-powered vacuum pump with filter for suctioning mucus from infant nasal passages showing our new design, with the tube portion shown in broken in the center to indicate indeterminate length;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a reduced perspective view showing the battery-powered vacuum pump with filter for suctioning mucus from infant nasal passages; the broken lines depict environmental structure for illustrative purposes only and form no part of the claimed design.
